CIGAR LIGHTER

John Sinko, Chicago, Ill.

Application September 7, 1935, Serial No. 39,561

10 Claims. (Cl. 219—32)

This invention relates to cigar lighters of the type used in automobiles, and more particularly to the kind known as the "wireless type" because a separable plug is provided which is first heated 5 in a socket and may then be removed from the socket for lighting a cigar, cigarette or pipe.

Cigar lighters of this general type have been known for some time, and in fact some of these are disclosed in my co-pending applications, 10 Serial Nos. 724,849 and 25,968, of which the present invention may be considered in some respects an improvement. Lighters of this type have usually, if not always, included a metallic socket into 15 which the igniter plug was inserted and which included the connections for the plug. Usually the socket, being grounded to the car, formed one contact while the other was carried by and in the base of the socket and therefore had to be 20 carefully insulated therefrom. The insulation of these parts always involved trouble and expense.

The present invention avoids this difficulty by forming the socket mainly of an insulating material so that no insulation of the inner terminal from the socket is necessary. The ground contact is formed by a metal ring which serves the 25 additional purpose of securing the socket to the instrument panel of the automobile.

It is an object of the present invention to provide 30 a cigar lighter of a simplified and yet thoroughly dependable construction.

It is a further object of the invention to provide 35 a socket for a cigar lighter of an insulating material which does not need to be insulated from either contact of the lighter and which is nevertheless sturdy enough to hold a contact in its base and to withstand the force applied to it during use.

Another object of the invention is to provide 40 an inexpensive socket for a cigar lighter which is capable of being rigidly attached at its open end to the instrument panel of an automobile.

Other objects and advantages of my invention 45 will be apparent from the following description, taken with the drawing, in which:

Fig. 1 is a vertical longitudinal sectional view 50 of one form of my invention chosen for illustration, shown attached to an instrument panel of an automobile.

Fig. 2 is a sectional view taken along the line 2—2 of Fig. 1.

Fig. 3 is a fragmentary sectional view of a modified form of socket.

Fig. 4 is a view similar to Fig. 1, but of a 55 modified form of the invention.

Fig. 5 is a sectional view of a socket coupler ring as found in the structure of Fig. 4.

Fig. 6 is a sectional view of the structure shown in Fig. 3, but showing a modified form of plug.

Fig. 7 is a fragmentary view showing a different 5 form of clamping nut.

Although this invention may take numerous forms, only a few have been chosen for illustration. They all include a socket member or a housing 11, a coupling member 12 permanently 10 secured thereto, a securing ring 13 screwed into said coupling member 12 and drawing the same against a suitable support, such as an instrument panel 14. The housing 11 is preferably a cup-shaped member molded from an insulating material such as that known commercially as "Bakelite". The coupler 12 includes an internally threaded portion 16 and a flange 17 of which the portion 18 may be rolled over behind a shoulder 19 formed on the housing 11, thus securing the 20 two together as a unit. In Fig. 7 a different manner of attachment is shown, the coupler ring 12² being screwed into housing 11². In any event the use of the coupler ring insures the secure attachment of the lighter to the panel, since there 25 is no attachment strain on Bakelite threads. To prevent the housing 11 from rotating within the sheathing 12, a lug 21 formed on the coupler 12 may be bent down into a recess in the housing 11, as illustrated. The coupler 12 may desirably 30 have a portion 23 of smaller diameter than the threaded portion 16, and in the form shown in Fig. 1 an inwardly extending flange 24 is provided. Extending through a hole at the base of the housing 11 is a screw 26 which secures a cup 35 or other contact member 27, as shown. The screw 26 may be swedged under its head to form lugs 28 engaging recesses in the housing 11 to prevent the screw from turning. The screw is drawn tight by a nut 29. A wire 31 connected to the 40 battery of the automobile is secured to the screw by another nut 32.

The removable lighter plug may be of any suitable form, three forms being illustrated. In all three forms there is a handle 36, preferably translucent or transparent, to which is secured a sleeve 37 which may be formed of Bakelite, a metal, or any other suitable material. In the form shown in Fig. 1 there is screwed into the sleeve 37 a support member 38 having spokes 39 and a central hub 41. To this central hub is secured a flat sided screw 40 carrying an igniting unit including a spoked cup 42 and a suitable resistance element 43. Slidably telescoping within the support member 38 is a contact ring 44 having 55

an outwardly extending annular flange 46 which may be flat or curved as shown, and an inwardly extending annular flange 47 as illustrated. The contact ring 44 is urged toward or against the ignition unit cup 42 by a suitable spring 48.

When the plug of Fig. 1 is inserted into the socket it moves inwardly easily until the flange 46 strikes the flange 24, at which time further movement will be opposed by the spring 48. 10 When it is desired to use the igniter, sufficient pressure is applied to the handle 36 to press the major portion of the plug inwardly against the compression of the spring 48 until the rim of the ignition element cup 42 comes in contact with the 15 contact member 27. At that time a circuit is established from the wire 31 through the screw 26, the cup 27, the rim 42, the resistance ribbon 43, the center stud 40 (which is insulated from the cup 42), the support member 38, the spring 48, 20 the contact ring 44, the coupler 12, and to ground at the instrument panel 14. When current flow has heated the resistance ribbon 43 to incandescence, its glow is visible through the handle 36, especially through the shoulder at the base thereof, and the plug may then be removed from the 25 socket and the hot ignition element applied to a cigar or cigarette.

To normally retain the plug in the socket, unless it is drawn out intentionally, a suitable frictionizer is provided. Three forms of this frictionizer are shown—one in Figs. 1 and 2, one in Figs. 3, 6 and 7, and the third in Fig. 5. Any frictionizer could be used in any figure. In Figs. 1 and 2 the frictionizer comprises a ball 51 30 pressed by a spring 52 through a hole 53 in the coupler 12 and against the side of the plug. The spring 52 may desirably be mounted in a screw cup 54 screwed into the housing 11, as illustrated.

The frictionizer in Fig. 3 comprises a coil spring 40 56, the convolutions of which are of very small diameter. The spring has its ends joined to form an endless band and is stretched around the reduced portion 23 of the coupler 12 and between it and the housing 11. The reduced portion 23 is 45 provided with a suitable slot 57 of such dimensions as to permit the spring 56 to draw itself partially therethrough, sufficiently to press against the plug as it is inserted into the socket. To prevent jamming, the spring 56 should not extend 50 quite half of its diameter through the slot 57.

In Fig. 5 the frictionizer is formed by the reduced portion 23' of the coupler 12' which is slotted, as at 61, the portions 62 adjacent the slot being biased inwardly to press against the plug 55 as it is inserted in the socket.

In Fig. 4, a slightly different arrangement of the other parts has been illustrated, in which the frictionizer of Fig. 5 may be used, the spring being in the socket instead of on the plug. Here the spring is identified by numeral 66, and it may be positioned in the bottom of the housing 11, as illustrated, and may press either directly against the support member 38' of the plug or against a retaining ring 67, as illustrated. When the plug 60 is removed, the retaining ring 67 presses against the edge of the coupler 12'. It will be noted that in this instance the coupler ring 12' does not have the inwardly extending flange 24 formed thereon. The support member 38' is of a different shape 65 than the support member 38 and has the rim 42 of the ignition unit separated therefrom only by a suitable layer of insulation 69, the sliding contact ring 46 being omitted. In this form of the invention the plug normally comes to rest against 70 the spring 66, being held in place by the resilient

biased portions 62 of the coupler 12'. When the igniter is to be used, the plug is pressed inwardly, compressing the spring 66 until the rim 42 of the igniter unit engages the contact cup 27. The current then flows through the circuit, as traced 5 before, except that in the support member 38' it passes directly to the coupler 12'. The coupler 12' should be of such length and shape that the biased portions 62 engage the support member 38' even when the plug is pushed into the socket 10 as far as it will go.

In all forms of the socket the housing 11 may be provided with suitable ventilating openings. In Fig. 1 openings 71 are located at the side of the housing, while in Fig. 4 openings 71' are located at the end of the housing.

The heating ribbon and carrying cup assembly, which may be considered a part of this invention, is preferably of a form intended to be standard so that it may be readily used on various forms of plugs. This assembly, which will be described with reference to Fig. 1, may desirably include a cup 42 facing the base of the socket and a spiral of resistance wire or ribbon 43 secured at one end to the cup 42 and at the other end to 20 the head 76 of the bolt 40 which passes through the cup 42 and the hub 41 for securing the parts together. The cup 42 has one or more suitable apertures in its bottom, which may be the spaces between spokes 78 forming the base of the cup. 30 A collar 80 rests on a mica sheet 82 which in turn rests against the hub of the spokes 78 to keep the head 76 of the bolt 40 within the cup. The heating element 43 is electrically insulated from the base of the cup 42 including the said spokes 35 78, by the mica sheet 82, which sheet is cut to register with said spokes 78.

In Fig. 1 this assembly is secured to the support member 44 by the screw 40, and on the back of the base of the cup 42 is another insulating washer 83 which may be formed of mica, against which there is a nut 84 which clamps the cup 42 and mica 82 against the collar 80. Another nut 85, also screwed on the bolt 40, in turn clamps the nut 84 against the hub 41 or a spacer bushing, 45 thereby rigidly mounting the cup 42 on the support member. In Fig. 4 the heating element assembly is secured to support member 38' as shown, and as previously described.

In Fig. 6 a third form of plug has been illustrated. In this form a metallic sleeve 86, with rolled threads thereon, is screwed into the sleeve 31 of insulating material. A flanged metallic ring 87 is screwed into the sleeve 86. A cup 88 perforated or spoked at its bottom is slidably carried by the ring 87 and pressed thereagainst by a spring 89 which reacts against an annular flange 91 formed at the far end of the sleeve 86. The resistance element (not shown) is carried within the cup 42 which has spokes aligned with the 60 spokes of the cup 88. The cup 42 is insulated from the cup 88 by suitable layers of insulation 92 and is secured to the cup 88 by the bolt 40 on which the nut is threaded, as shown. The cup 42, the resistance element therein, the bolt 40 65 and the cup 88 may together be considered the heater assembly, although in a more narrow sense the cup 88 would not be a part of this assembly. With this form of plug the cup 42 normally engages the contact cup 27, and the circuit 70 is completed when the remainder of the plug is pushed in against spring 89 until the flanged ring 87 contacts the flange 24 on the coupler member 12. The circuit may be traced from the contact 75 27, through the cup 42 and the resistance ele- 75

ment, to the screw 40, through the cup 88, directly to the ring 87, or through the spring 89 and the sleeve 86 to the ring 87, and from the ring 87 through the coupler 12, to ground.

5 In assembling this structure the cup 88 is inserted through the ring 87 prior to attachment of cup 42 to the cup 88. After attachment of cups 88 and 42 by bolt 40, the spring 89 is placed in the cup 88 and the ring 87 screwed into the 10 sleeve 86. This forms a separate unit which may be secured in any suitable sleeve 37. It should be observed that this unit is quite similar to the unit in Fig. 1, which includes the resistance element, cup 42, ring 44, support member 38, and 15 spring 48, and the unit in Fig. 4 including the resistance element and cups 42 and 38'. All of these units are in the nature of separate spring and igniter units, and in all of these units tightening of the nuts 85 and alinement of the spokes 20 of the various members is facilitated by the flat sides of screw 40 which prevent rotation of the screw in the support member which has a correspondingly shaped hole. Alinement of the spokes is desirable to let light pass from the element when it is sufficiently hot, to the translucent handle 36.

Both of the units including springs are characterized by the very desirable feature that the thrust of the spring is taken up entirely by metallic members, the expansion of the spring 89, for example, being limited by engagement of the flange 94 on cup 88 with ring 87 which is screwed into cup 86. In short, the spring 89 and 48 never exert any force on the threads of the bakelite sleeve 37. This is important, since threads in such members as bakelite sleeve 37 are not dependable for such purposes. Furthermore, with the structure of Fig. 6 it is not necessary to depend upon possible sliding frictional contact between the ring 87 and cup 88 for a satisfactory electrical contact. This is accomplished positively with the spring 89 in continuous engagement with the cup 88 and flange 91 of the sleeve 86.

45 Although I have described my invention in its preferred embodiments, it is understood that I do not limit myself thereby, but limit the invention only by the scope of the appended claims.

I claim:

50 1. A cigar lighter including a housing formed of insulating material, a threaded coupler secured at one end of said housing, an outwardly flanged ring screwed into said coupler for securing it to a suitable conductive support member, a conductor carried by the other end of said housing, a removable plug including a resistance element and extending into said housing through said ring, and means for electrically connecting said resistance element to said conductor and to 55 said support member.

2. A cigar lighter including a housing formed of insulating material, a threaded coupler secured at one end of said housing, an outwardly flanged ring screwed into said coupler for securing it to a suitable support member, a conductor carried by the other end of said housing, a plug including an ignition element and extending into said housing through said ring, and means for connecting said conductor and at least one of said 65 coupler and ring members to said ignition element, said means including an inwardly extending flange on said coupler and a resiliently mounted contact member on said plug engaging said flange.

70 75 3. A cigar lighter including a cup-shaped

housing of insulating material, a coupler for said housing secured to the open end thereof, a securing ring screwing into said coupler to clamp the same against a support member, and a plug having a resistance element thereon and extending through said ring into said housing, said coupler having at its outer end a portion of reduced diameter for engaging said plug. 5

4. A cigar lighter including a housing of insulating material, a coupler for said housing secured to one end thereof, a securing ring screwing into said coupler to clamp the same against a support member, and a plug having a resistance element thereon and extending through said ring into said housing, said coupler having a slot therein, and a tension helical spring surrounding said coupler so as to be resiliently drawn into said slot for engaging the side of said plug. 10 15

5. A cigar lighter including a housing of insulating material, a securing coupler for said housing secured to one end thereof, a securing ring screwing into said securing coupler to clamp the same against a support member, and a plug having a resistance element thereon and extending through said ring into said housing, said coupler having a portion of reduced diameter for 20 25 engaging said plug, and a ball member carried by said housing and pressed against the side of said plug by a spring also carried in a cup screwed into and supported by said housing. 30

6. A cigar lighter including a housing of insulating material having an outwardly extending annular shoulder at one end, a coupler within said housing secured to said end thereof by a flange extending around and rolled back over said shoulder, a securing ring screwing onto said coupler to clamp the same against a support member, and a plug having a resistance element thereon extending through said ring into said housing, said coupler having a portion of reduced 35 40 diameter for engaging said plug.

7. A cigar lighter including a housing of insulating material having an outwardly extending annular shoulder at one end, a coupler within said housing secured to said end thereof by a flange extending around and rolled back over said shoulder, a securing ring screwing onto said coupler to clamp the same against a support member, and a plug having a resistance element thereon extending through said ring into said housing. 45

8. A cigar lighter including a housing of insulating material having an outwardly extending annular shoulder at one end, a coupler within said housing secured to said end thereof by a flange extending around and rolled back over said shoulder and having a lug extending into a recess in said housing member for preventing relative rotation thereof, a securing ring screwing onto said coupler to clamp the same against a support member, and a plug having a resistance element thereon extending through said ring into said housing, said coupler having a portion of reduced diameter for engaging said plug. 55 60

9. An assembled head for a cigar lighter comprising: an igniter unit having a threaded rearwardly extending conducting stem; a contact ring encircling said stem and having an inwardly extending flange providing a seat; a conducting compression spring having its front end resting in said seat; and a conducting support member 65 impaled by said stem and forming a seat for the rear end of said spring, said support member having its hub portion dished forwardly to form a recess for a nut adapted to hold the support member on the stem. 70 75

10. An assembled head for a cigar lighter comprising: an igniter unit having a rearwardly extending stem; a cup-shaped member having its front end connected to said stem and its rear open end provided with an outwardly extending flange; a second cup-shaped member provided with a threaded side wall having its open front and extending forwardly around the side wall

5 of the first mentioned member; a compression coil spring housed by said cup-shaped members so as to urge them to extended position; and a ring slidably mounted on the first mentioned member and threaded to the second mentioned member so as to limit their relative movement. 5

JOHN SINKO.
